FIG. 3 is a front elevational view thereof;

FIG. 4 is a rear elevational view thereof;

FIG. 5 is a top plan view thereof;

FIG. 6 is a bottom plan view thereof; and,

FIG. 7 is a right side view; the left side view is a mirror image thereof.

The ornamental design which is claimed is shown in solid lines in the drawings. A left-side elevational view is not shown because it is a mirror image to the right-side elevational view shown in FIG. 7.

1 Claim, 3 Drawing Sheets
